UNITED STATES PATENT OFFICE.

JOHN RAPHAEL ROGERS, OF BROOKLYN, NEW YORK, ASSIGNOR TO MERTHALER LINOTYPE COMPANY, A CORPORATION OF NEW YORK.

LINOTYPE-MACHINE.

No. 846,053.

Specification of Letters Patent.

Patented March 5, 1907.

Application filed August 17, 1906. Serial No. 330,985.

To all whom it may concern.

Be it known that I, JOHN RAPHAEL ROGERS, of the borough of Brooklyn, county of Kings, and State of New York, have invented a new and useful Improvement in Linotype-Machines, of which the following is a specification.

My invention has reference to linotype-machines wherein the composed line of matrices is presented temporarily against the face of a slotted mold in order to close the same and form type characters in relief on a type-metal slug or linotype cast in said mold, as shown, for example, in Letters Patent of the United States No. 436,531. In these machines the matrices, having protruding ears at the lower end, are suspended in a vertically-movable support known as the "first elevator" and indicated by t^2 in the drawings of said patent, and after the matrices are in the casting position the elevator is urged upward, so as to press the ears of the matrices against the under side of a horizontal shoulder or ledge on the mold. This shoulder serves not only to insure the proper alignment of the matrices horizontally, but also to determine the position of the matrices proper in relation to the mold-slot, and consequently the position of the type characters on the edge of the slug or linotype.

In machines as heretofore constructed the shoulder was fixed in relation to the mold-slide, and with given matrices it was impossible to change the location of the characters on the slug—that is to say, impossible to set them nearer the upper or the lower edge, if required. In practice it frequently happens that it is desirable to shift a line of characters edgewise of the slug toward its upper or its lower edge, as the case may be, in order to accommodate accents or characters having an unusual length above or below their body portions. I accomplish this result by changing the relation of the matrices to the mold-slot, and in order that this may be done I provide in connection with the mold and preferably attached thereto an adjustable alining-bar or ledge to engage the ears of the matrices. This bar, lying parallel with the mold-slot, may be moved toward or away from the same at will to any desired extent. In this manner the matrices may be adjusted endwise so that they will be presented along the center of the mold-slot or

above or below the center, as demanded, the result being that the type characters produced will occupy corresponding positions on the edge of the slug.

In the accompanying drawings I have shown my invention as applied to an adjustable mold of the type ordinarily used in commercial linotype-machines of the present day and represented in Letters Patent of the United States No. 620,804.

Figure 1 is a face view of a mold having my improvement applied thereto. Fig. 2 is a cross-section of the same on the line 2-2. Figs. 3 and 4 are diagrams illustrating the action of my improved device.

Referring to the drawings, A represents the mold proper secured in a vertical supporting-wheel B and containing the mold-slot a , which extends therethrough from the front to the back.

C C represent the matrices, each containing the intaglio character or matrix proper, c , in one edge and having shoulders c^1 and c^2 at the upper and lower ends. These matrices in action are assembled in line side by side and the entire line suspended in the vertically-removable support D directly in front of the mold, the individual matrices standing edgewise against the mold with the matrix proper, c , opposite the mold-slot, so that the metal delivered into the slot to form the slug or linotype will also flow into the matrices, which will produce the type characters in relief on the edge of the slug.

E represents the alining-bar secured to the face of the mold, its form being such as to overlap the ears c^2 of the matrices, so that when the matrices are urged upward by means of the elevator D their ears will be pressed against the under side of the shoulder, whereby the matrix-bodies and the characters therein will be brought into exact alignment horizontally.

It will be observed that the distance between the shoulder and the alining-bar and the mold-slot determines the position of the matrices c vertically in relation to the mold-slot. By raising and lowering the plate E the operative position of the matrices may be changed vertically so that the characters therein will appear opposite the center of the mold-slot, or near its upper side, as shown in Fig. 3, or its lower side, as shown in Fig. 4, as occasion may require. In other words, the

- vertical adjustment of the plate E will determine the position of the type characters on the slug or linotype with reference to its upper and lower sides. In this way the type characters, if small, may be placed near the upper side of a thick slug, so as to leave a wide blank space below them, or they may be located near the lower side of the slug, so as to leave a blank space above them.
5. Matrices representing accented characters which will occupy nearly the full width of the slug may be adjusted in the exact positions required to bring the entire character on the edge of the slug.
10. In order to effect accurate adjustment of the alining-plate E and to hold it in exact parallelism with the mold-slot, I may use devices of any suitable character; but I recommend the arrangement shown in the drawings, consisting simply of a horizontally-movable plate or slide F, seated in the under or lower edge of the mold and provided with a longitudinal groove f, inclined from the horizontal and adapted to receive a corresponding rib on the back of the alining-plate. By moving the slide F to the left the plate E will be lowered and the type characters produced in lowered position on the edge of the slug, while, on the other hand, the movement of the slide F to the right will raise the plate E, permit the matrices to assume a higher relation to the mold-slot, and consequently produce type characters in a higher position on the edge of the slug.
15. The plate E is secured in place by binding-screws G, extended through slots therein into the body of the mold. By tightening these screws the plate and slide may be secured firmly in their adjusted positions. The screws may be continued through into the mold-supporting wheel, as shown in Fig. 2, so that they will serve also the additional purpose of holding the mold-body in place; but this is not necessary, as the mold may be secured by independent means.
20. The body of the mold may be of any construction desired, provided only it contains the slot or cell a and is adapted to receive an adjustable alining-plate E.
25. The plate E, as shown in Figs. 1 and 2, is provided with two parallel shoulders e and e', to engage the matrices, and this for the purpose of permitting the use of ordinary two-letter matrices—that is to say, matrices containing in the edge two separately-usable characters, requiring the matrices to be set at different heights in relation to the mold for the production of the respective characters.
30. It is to be noted that the embodiment of my invention in the form herein shown admits of its being applied to linotype-machines

of ordinary construction without necessitating any other change in the molds and without requiring adjustment of the mold proper or change in the position of the ejecting devices which coöperate therewith. 65

In the form of the mold herein shown the upper portion or cap forming the type-wheel of the slot is separated from the body portion by intermediate removable liners at the ends, 70 as usual, it being the practice to remove these liners and substitute others in order to change the length or the height of the mold-slot and the dimensions of the slugs produced therein. It will of course be understood that the dimensions of the slot may be varied in this way or otherwise without in the least affecting the operation of my attachments. 75

Having described my invention, what I claim is—

80. 1. In a linotype-machine, and in combination with a slotted mold, a matrix-alining plate movable toward and from the mold-slot, and means for positively moving said plate and securing it in its different positions. 85
2. In a linotype-machine, the combination of a slotted mold-body, a matrix-alining plate movably secured to the mold parallel with the slot, means for moving said plate toward and from the slot, and distinct means 90 for securing the plate in any desired position.
3. In combination with a slotted mold-body, a matrix-alining plate movable toward and from the slot, and a slide having an inclined bearing-surface for the purpose of adjusting said plate. 95
4. In combination with a slotted mold-body, a matrix-alining plate, the adjusting-slide connected therewith by an inclined sliding joint. 100
5. The combination of a slotted mold-body, the matrix-alining plate E, a slide F for adjusting said plate and binding-screws, substantially as shown. 105
6. In a linotype-machine, the combination of a slotted mold, coöperating matrices containing each two independent characters, an alining-plate E movably attached to the mold and provided with two grooves or shoulders e, e', means for moving the plate toward and from the slot and maintaining its parallelism therewith, and means for holding the plate in its different positions; whereby either character of the matrices may be held in different relations to the mold-slot. 110

115. In testimony whereof I hereunto set my hand, this 13th day of August, 1906, in the presence of two attesting witnesses.

JOHN RAPHAEL ROGERS.
